UNITED STATES PATENT OFFICE.

THOMAS E. BARR, OF KALAMAZOO, MICHIGAN.

INSECT-EXCLUDER FOR WINDOW-SASHES.

SPECIFICATION forming part of Letters Patent No. 618,825, dated February 7, 1899.

Application filed November 23, 1896. Renewed June 18, 1898. Serial No. 683,870. (No model.)

To all whom it may concern:

Be it known that I, THOMAS E. BARR, a citizen of the United States, residing at the city of Kalamazoo, in the county of Kalamazoo and 5 State of Michigan, have invented certain new and useful Improvements in Insect-Excluders for Window-Sashes, of which the following is a specification.

My invention relates to improvements in 10 insect-excluders for window-sash.

In window-sash such as ordinarily constructed when the lower sash is raised or the upper one is lowered there is a considerable space between the two, through which insects 15 can readily pass and enter a room whether there be screens or not, unless of course the screens are placed over the entire window or are under the outside sash.

The objects of my invention are to provide 20 an effective excluder for use between the meeting-rails of a sash that will extend from one rail over into close proximity with the window-pane of the opposite sash and that can be provided with automatic means or other 25 suitable means for actuating the same to move it out of the way, so that the mullions of the sash can pass the same or so that the bottom rail of the lower sash or the top rail of the upper sash will pass the same, as the 30 case may be, depending on the location of the excluder.

A further minor object is to provide an improved means whereby a strip of light material, such as celluloid or other hard fiber or 35 any similar material, can be readily inserted into the excluder, but can be easily renewed in case of accident or in case the same becomes soiled or injured in any way.

Still further objects will appear definitely 40 in the detailed description.

I accomplish these objects of my invention by the devices and means described in the following specification and illustrated in the accompanying drawings, in which—

45 Figure 1 is a vertical transverse sectional view of a window-frame on a line corresponding to line 1 1 of Fig. 2, showing details of construction. Fig. 2 is a sectional view on line 2 2 of Fig. 1. Fig. 3 is an elevational view, 50 the mechanism at the end of the meeting-rails of the sash being shown in section. Fig. 4 is a detail sectional view on line 4 4 of Fig. 1,

showing the means of adjusting the operating mechanism.

In the drawings all of the sectional views 55 are taken looking in the direction of the little arrows at the ends of the section-lines, and similar letters of reference refer to similar parts throughout the several views.

Referring to the lettered parts of the drawings, A A' represent the meeting-rails of the upper and lower sash, respectively. On the under side of the meeting-rail of the upper sash is secured the tubular shell B, made of sheet metal, having the two edges of the metal 65 extended to one side. Between these extended sections of sheet metal is secured the plate B', formed with bearing-arms, having hooks toward the outer edge, into which is inserted a thin sheet of celluloid or other suitable ma- 70 terial B'', which projects up close to the glass of the opposite sash. Inserted into one end of the tubular shell is a spiral spring G, one end of which is secured to the casing B and the other end of which is extended outward 75 and rests upon or is inserted into the meet- ing-rail of the sash. Over the shell B are inserted staples C, which retain the same in position and permit of a rocking of the casing inside of the staples, as is clearly indicated 80 in Figs. 1 and 3.

At the end of the shell B is secured a lever F on a pivot S, and a suitable stop H extends from the extended portion of the sheet metal forming the shell B and supports the lever 85 in position. The upper side of the lever is positioned to rest against a round wire staple I or other suitable support or fulcrum or di- rectly against the edge of the sash, for that matter, when the sash is of suitable material. 90 The end of the lever F projects out toward the opposite sash to fit close to the stile thereof. There should be a lever F at each end unless the window is very narrow. On the stiles K are placed suitable pins or stops 95 J, positioned to actuate the lever F when the lower sash is raised or the upper sash is lowered, as the case may be. It will be ob- served that when either sash is moved and the insect-excluder approaches one of the 100 mullions or the top of the bottom rail of the sash, as the case may be, the lever F will come in contact with the pin or stop J and will ac- tuate the shell B, throwing down the insect-

guard B", allowing it to pass the mullion of the bottom rail of the sash, as the case may be, and close automatically into place below to form a perfect excluder.

5 At the center of the meeting-rail of the sash is provided a knob D', connected to a suitable rod or rack D below, which meshes cogs at the center of the shell. This is provided with a stop E to engage under a pin n 10 on the rod D to retain the same in the elevated position. Thus it will be seen that when it is desired the insect-excluder can be thrown down and out and secured there by merely pulling up on the knob and stopping 15 it in the elevated position. I desire to state that in some styles of windows, such as the windows having very large panes without mullions across them, this actuating-rack will do all that is required, for all that is required is that the excluder be moved so that 20 the bottom rail passes the meeting-rail of the upper sash or the top rail of the upper sash passes the meeting-rail of the lower sash when the windows are being cleaned, and of course automatic action is not required. 25

A special reference is made to the top rail of the upper sash or the bottom rail of the lower sash in view of the fact that this insect-excluder is capable of being used on the top 30 of the bottom sash by merely reversing its parts, and I do not desire to be limited to the excluder located in one place. I also desire to state in this connection that my improved excluder could be actuated in other ways, 35 where it is not necessary or desirable to have it operated automatically, and answer its purpose very well. I will say, however, that an insect-excluder of this style in order to be successful must be pivoted to the sash so it 40 can be turned out of the way of at least the top rail or the bottom rail of the sash to permit the windows to be moved past each other.

From what has been said it must be clear 45 that my improved insect-excluder can be greatly varied in its details and arrangement without departing from my invention. I desire to add that I have shown the construction in its most approved form. I am aware that the pivoting or hinging could be different and also that there are a great variety of 50 means for adjusting the same.

Having thus described my invention, what I claim as new, and desire to secure by Letters Patent, is—

55 1. In an insect-excluder for window-sashes the combination of the meeting-rails A, A', the excluder consisting of the shell B, pivotally secured to one of the meeting-rails by suitable staples C, and containing a coiled 60 spring to actuate the same and retain it normally against the meeting-rail; a strip of suitable material as celluloid projecting therefrom across to the opposite window-pane; a lever F, pivoted to said shell and extending 65 therefrom across the opposite stile of the opposite window-frame; a stop H, to support said lever; a fulcrum I, on which the said le-

ver acts and the stop J, on the opposite window-stile to act upon the lever and throw down the excluder when the sash are moved 70 so that the excluder can pass a mullion of the sash or one of the rails thereof all coacting together substantially as described for the purpose specified.

2. In an insect-excluder for window-sash 75 the combination with the meeting-rails of a strip of suitable material pivotally supported on one of said meeting-rails and suitable means of actuating and adjusting the same so that the excluder can pass the mullion or 80 rails of the sash when the window is operated.

3. In an insect-excluder for window-sash the combination of the meeting-rails of the sash of a casing D, pivotally secured to one of the rails and embracing a sheet or strip 85 of suitable material projecting across to the window-pane of the opposite sash and suitable means of actuating the same to keep the excluder out away from the opposite sash during the operation of the window as speci- 90 fied.

4. In an insect-excluder for window-sash the combination with the meeting-rails of the sash of a suitable flat strip pivoted to one of said meeting-rails and extending across to 95 the pane of the opposite sash; a rack D, extending through said rail and meshing with suitable cogs secured to the strip and means of adjusting the rack to adjust the excluder as specified. 100

5. In an insect-excluder for window-sash the combination with the meeting-rails of the sash of a suitable flat strip pivoted to one of said meeting-rails and extending across to the opposite pane; a lever pivoted to act on said 105 excluder to turn the same; and a stop on the opposite window to strike said lever to actuate the excluder automatically when necessary for the purpose specified.

6. In an insect-excluder for window-sash 110 the combination with the meeting-rails of the sash of a suitable flat strip pivoted to one of said rails and extending across to the opposite pane; a strip to hold said strip in position; a lever pivoted to said strip and ful- 115 crumed on the sash-rail; a stop on said strip to support said lever; a stop on the opposite sash to contact with said lever to actuate the same for the purpose specified.

7. In an insect-excluder for window-sash 120 the combination with the meeting-rails of the shell B, pivotally supported on one of them, bearing-arms flexible at their tips forming hooks; and a sheet of celluloid or like material inserted into the side of the shell and 125 retained by the flexible ends folding onto the same as specified so that the strip can be easily renewed.

In witness whereof I have hereunto set my hand and seal in the presence of two witnesses. 130
